UNITED STATES PATENT OFFICE.

ROY F. GOULD, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed August 28, 1925. Serial No. 53,030.

This invention relates in general to automatic telephone systems, in which connections are established through the medium of subscriber controlled automatic switches, but is more particularly concerned with automatic systems including party lines, and the object of the invention is to provide a new and improved method of and apparatus for selectively signaling the party line stations. The arrangement herein described is simple and inexpensive and on that account is especially well adapted for use in small systems, such as private automatic exchanges, although its use is not necessarily so limited. The means by which the foregoing object is accomplished will be fully set forth hereinafter, reference being had to the accompanying drawing, in which is shown sufficient of the apparatus in a small automatic telephone system to enable the invention to be explained and understood.

The reference character A indicates an automatic substation of the grounded bell type, which has the usual talking instrumentalities and the calling device S for controlling the central office switches.

Substation A is connected with the central exchange by line conductors 11 and 12 which terminate in the individual line or trunk selecting switch C. The line switch C is a switch of the well known rotary type whose wipers have no normal position and move in a forward direction only. As is well known, the function of the individual line switch is to extend its associated line to an idle selector switch or connector switch when the receiver is raised at the substation to initiate a call.

One of the connector switches, to which the line switch C has access in the instant case, in common with other similar line switches, is indicated in the drawing by the reference character E. It may be stated briefly that the connector E is a Strowger vertical and rotary switch of well known mechanical construction, and operable according to the two-wire system of control. It has a capacity of one hundred subscribers' lines and responds to three digits. The first digit is used to accomplish the ringing selection by operating or not operating shaft spring 97, positioned so as to close its contact on some level above the first level, as for instance the third, and the switch always releases after the first digit. The second and third

digits are used to operate the connector in the usual manner to complete the connection to the called line.

One of the lines to which the connector E has access is shown at the upper right hand corner of the drawing and comprises line conductors 111 and 112. This line is a two-party line, and substations A¹ and A² are connected in bridge of the line with their bells grounded in the well known manner. The line switch C¹ is associated with the party line at the exchange, and is similar to the line switch C.

Having described the equipment and the apparatus in general, a more detailed description of the various operations will now be given. For this purpose, it will be assumed that the subscriber at substation A desires to establish a connection with a subscriber at substation A¹, whose telephone number is 284.

When the receiver is removed at the calling station, a circuit is completed over the line conductors 11 and 12 for the slow acting line relay 14. Upon energizing, relay 14 closes a circuit at its armature 17, which includes the winding of the switching relay 15 and the stepping magnet 16 in series; and at its armatures 18 connects the test wiper 26 to the above circuit at a point midway between the said switching relay and the magnet. The operation now depends upon whether the trunk line with which the line switch wipers are associated is busy or is not busy. If the trunk line is busy, there will be a ground potential upon the said contact with which the test wiper 26 is in engagement, the switching relay 15 will be short circuited, and the stepping magnet 16, which interrupts its own circuit, will be operated in the manner of a buzzer to advance the switch wipers in search of an idle trunk line. We may assume, in the present case, that when the call is initiated the wipers are advanced to the idle trunk terminating in bank contacts 28-30, inclusive. When the wipers arrive at this set of contacts the short circuit is removed from the switching relay 15 and the operation of the stepping magnet 16 will cease because of the high resistance of the said switching relay. The latter relay, however, is energized and grounds the test wiper 26 at its armature 20, and at its armatures 19 and 21 disconnects the line conductors 11 and 12 from

ground and from the winding of the line relay 14, respectively, and extends them by way of wipers 25 and 27, and bank contacts 28 and 30 to the line relay 50 of the connector 5 E. When the line is extended as above described, the line relay 50 is energized over the line circuit to close a circuit for the slow to release relay 51. Upon energizing, relay 51 prepares a circuit for the vertical magnet 10 59 at its armature 68, and at its armature 67 connects ground to the release trunk conductor 49, thereby completing a holding circuit for the line switch C in the well known manner.

15 The calling subscriber may now operate his calling device in accordance with the first digit in the desired number. In response to the interruptions in the line circuit thus produced, the line relay 50 is deenergized twice, 20 and at the first deenergization transmits a current impulse to the vertical magnet 59 over the following circuit: Grounded armatures 66 and its resting contact, working contact and armature 68, resting contact and 25 off-normal spring 64, winding of the slow to release series relay 53, and the winding of the vertical magnet 59 to battery. By the operation of the vertical magnet, the wipers 91-93, inclusive, are raised step by step 30 until they stand opposite the dialled level, which in the present instance is below the level where the shaft of the switch operates the spring 97, as previously pointed out. The slow to release series relay 53 is energized in series with the vertical magnet and 35 by means of its armature 73 maintains the circuit of the vertical magnet intact after the regular off-normal springs have been shifted, which occurs on the first vertical 40 step. At the end of the vertical movement of the switch, relay 53 is deenergized and closes a circuit for release magnet 61 at armature 72 which may be traced from grounded armature 69 and its resting contact, resting contact and armature 72, off normal 45 spring 63 and its working contact, and release magnet 61 to battery. Release magnet 61, upon energizing, releases the shaft carrying the wipers 91-93, inclusive, allowing the same to restore to normal and open the off normal springs in the well known manner. As a further result of the energization of the release magnet 61, a circuit is 50 closed at armature 65 for relay 52 which may be traced from grounded armature 67 and its working contact, armature 65 and its working contact, lower winding of relay 52, armature 71 and its resting contact, and release magnet 61 to battery. Relay 52 does 55 not, however, energize over this circuit until the shunt at the armature 62 is removed by the opening of the off normal springs. When the shunt is removed relay 52 energizes and locks up to ground at armature 67, 60 by way of its armature 70, which armature

is adjusted to make before armature 71 breaks. At armature 69, relay 52 removes ground from the contact of armature 72 and the shaft spring 97 (the latter operation being effective to prevent relay 58 from 70 energizing on the second digit regardless of the value of such digit); and at armature 71 opens the circuit of release magnet 61. Release magnet 61, upon deenergizing, opens the initial energizing circuit of relay 52 at 75 armature 65.

The calling subscriber may now operate his calling device in accordance with the second digit in the desired number, the digit 80 3. In response to the interruptions in the line circuit thus produced, the vertical magnet of the connector is again operated under control of the line relay to raise the wipers 91-93, inclusive, to the particular level in which is terminated the line including substation A¹, in the manner already described above. At the end of the vertical movement of the switch, relay 53 deenergizes and transfers the operating circuit from the vertical magnet 59 to the rotary magnet 60. The previously traced operating circuit for the release magnet 61 is open at armature 69, and although shaft spring 97 is now actuated, relay 58 does not energize.

The subscriber will now operate his calling device in accordance with the next and last digit of the desired number, the digit 95 4. When the calling device is operated, the line relay 50 responds as before and sends impulses to the rotary magnet 60 over the following circuit: Grounded armature 66 and its resting contact, working contact and armature 68, normally open contacts controlled by the off-normal spring 64, armature 73 and its resting contact, stepping relay 54, resting contact and armature 78, resting contact and armature 82, and rotary magnet 60 to battery. By the operation of the rotary magnet, the wipers 91-93, inclusive, are rotated step by step and are finally brought to rest in engagement with the bank contacts on which the line including substation A¹ is terminated. These bank contacts are indicated in the drawing by the reference characters 94, 95 and 96. The slow to release relay 54 is energized in series with the rotary magnet and retains its armature attracted throughout the rotary movement of the switch. At its armature 75, relay 54 connects test wiper 92 with the test relay 56, and at its armature 74 the said relay 54 closes a shunt around the contact at armature 82 of the test relay. The latter operation is to prevent the test relay from opening the rotary magnet circuit while the test wiper is passing over busy test contacts.

120 It will be assumed first that the called line is busy. Such being the case, when the test wiper 92 arrives at test contact 95, it 125 130

will find a ground potential thereon, and the test relay 56 will be energized over a circuit which may be traced from grounded test contact 95, test wiper 92, armature 75 and its working contact, resistance 76, resting contact and armature 85, and upper winding of test relay 56 to battery. The resistance 76 is inserted to prevent the relay from heating up through its low upper winding to ground direct. When the slow to release relay 54 deenergizes at the end of the rotary movement of the switch, the test relay 56 establishes a locking circuit for itself at its armature 83 which may be traced from ground on the release trunk conductor 49, armature 83 and its working contact, normally closed contacts controlled by armature 75, resistance 76, resting contact and armature 85, and upper winding of the test relay 56 to battery. Relay 56 also opens the rotary magnet circuit at its armature 82, thus rendering the impulse circuit ineffective at this time in case the calling subscriber dials another digit in error. Relay 56 also, at its armature 84, connects a lead from the busy signaling machine, labeled "Busy", to the lower talking conductor. By this latter operation, an audible signal is transmitted to the calling subscriber, and, being advised thereby that the called line is inaccessible for the time being, he will hang up his receiver.

Having explained the operation which takes place when the called line is busy, it will now be assumed that the line is idle when called. Under these circumstances, when the test wiper 92 arrives at the test contact 95, it will find no ground potential and the test relay 56 will not be energized. Then when the slow to release relay 54 deenergizes at the end of the rotary movement of the switch, a circuit is completed for the switching relay 55 as follows: From the grounded release trunk conductor 49, armature 83 and its resting contact, lower winding of switching relay 55, resting contact and armature 75, test wiper 92, bank contact 95, winding of the switching relay 116, and the winding of the stepping magnet 114 to battery. Relays 55 and 116 are energized in series over the above circuit, and the latter relay is operated to clear the called line of its normal battery and ground connections in the line switch C¹. It should be noted that the relay 116 is not fully operated at this time, due to a mechanical interlocking arrangement between the armature of this relay and the armature of slow acting line relay 115, and the wipers of the line switch C¹ are not connected up. In the connector E, when the switching relay 55 is energized, it establishes a locking circuit for itself at its armature 79, grounds the test wiper at armature 77, opens the impulsing circuit of magnet 60 and prepares a circuit for slow

acting ring cut-off relay 57 at armature 78, and closes at armature 81 the signaling circuit which may be traced from grounded generator GEN, through the contacts of the ringing interrupter, resting contact and armature 87, armature 81 and its working contact, resting contact and armature 90, line wiper 93, bank contact 96, line conductor 111, and through the condenser and bell by way of the switchhook at the called substation A¹ to ground. The above circuit is intermittently opened and closed by the operation of the ringing interrupter and the ringer at substation A¹ is thus operated at intervals to signal the called subscriber. As a further result of the energization of switching relay 55, a circuit is closed at armature 80 which provides for transmitting a tone signal to the calling subscriber during the ringing operation. When the called subscriber at substation A¹ removes his receiver to answer the call, the ringer thereat is disconnected and the ringing circuit is completed over a metallic circuit including the other line conductors 112 and the upper winding of the ring cut-off relay 57 at the connector E, which may be traced as follows: Grounded generator GEN, through the contacts of the ringing interrupter, resting contact and armature 87, armature 81 and its working contact, resting contact and armature 90, line wiper 93, bank contact 96, line conductor 111, through the receiver, transmitter and calling device of the substation A¹ to the line conductor 112, bank contact 94, line wipers 91, armature 88 and its resting contact, top winding of the ring cut-off relay 57, working contact and armature 78, resting contact and armature 82, and rotary magnet 60 to grounded battery. The rotary magnet will not energize over this circuit but the ring cut-off relay 57 energizes and establishes a locking circuit for itself at armature 86 to the grounded release trunk conductor 49, opens the ringing circuit at armature 87, and at the latter armature and armature 85 finally completes the talking circuit.

The required connection has now been established and the calling and called subscribers may converse as desired. Current for the transmitter at substation A is supplied through the windings of relay 50, and current for the transmitter at substation A¹ is supplied through the windings of the test or busy relay 56, now used as a back bridge relay, which circuit may be traced from grounded release trunk conductor 49, armature 86 and its working contact, lower winding of busy relay 56, working contact and armature 87, armature 81 and its working contact, resting contact and armature 90, line wiper 93, bank contact 96, line conductor 111 over the called subscriber's loop and return to line conductor 112, bank contact

94, line wiper 91, armature 88 and its resting contact, working contact and armature 85, and upper winding of relay 56 to battery. Relay 56, upon energizing, disconnects 5 the rotary magnet 60 at armature 82, and connects the busy machine at armature 84, but the latter is of no consequence at this time as the busy circuit is now open at the normally closed contacts controlled by armature 87.

When the conversation is finished, both subscribers will hang up their receivers. When the receiver is replaced at substation A, the line and release relays 50 and 51 are deenergized and the latter relay disconnects 15 ground from the release trunk conductor 49, thereby causing relays 52, 55, and 57 to de-energize, and line switch C to restore to normal. Relay 52, upon deenergizing, closes a 20 circuit for release magnet 61 at armature 69, which circuit has already been traced, and which operates to restore the connector E to normal position in the usual manner.

A brief explanation will now be given of 25 the manner in which the other station on the line is signalled. Substation A² may be assigned the telephone number 334, the first digit 3 corresponding to the level at which the shaft spring 97 is actuated. The operations 30 are exactly the same as when substation A¹ is called, except that when the shaft spring 97 is operated on dialling the first digit a circuit is closed for wiper reversing relay 58, which may be traced from ground- 35 ed armature 69 and its resting contact, shaft spring 97 and its working contact, normally closed contacts controlled by armature 89, and wiper reversing relay 58 to battery. Relay 58, upon energizing, closes a locking 40 circuit for itself at its armature 89 to the release trunk, and at its armatures 88 and 90 switches the wipers so that the signaling current is now sent over line conductor 112, instead of 111, to ring the bell at substation 45 A².

In the foregoing, a specific system has 50 been assumed in which those subscribers whose ringers are connected like the ringer at station A', that is, to the positive side of the line, have telephone numbers beginning with the digit 2; while those subscribers whose ringers are connected to the other sides of their respective lines have telephone numbers beginning with the digit 3. It will be 55 understood, however, that some variation from this is possible because the reversing relay 58 energizes if the digit 3 or any larger digit is called as the first digit, and will not energize if the first digit is less than 60 3; consequently, subscribers in the first mentioned class may have telephone numbers beginning with either 2 or 1, while subscribers in the second class may have telephone numbers beginning with any digit from 3 to 65 0, inclusive.

It will be understood also that some or even a majority of the lines in the system may be individual lines rather than party lines. The telephone numbers of individual lines may begin with any digit since only one station on a line need be considered, the ringer being connected to either positive or negative side of the line, depending on the value of the first digit.

The possibility of varying the first digit 75 in telephone numbers that exists in this system is often of convenience to operating telephone companies. In the case of a private exchange located all in one building, for example, the first digit may be used as a floor designation, as well as to accomplish the station selection, while if the stations are scattered in various buildings, the first digit in the number of any station may correspond to the building in which such station is located. In the case of party lines, of course, the two stations on any line must be located 80 on different floors, or in different buildings, in order for this scheme to be followed.

Having described my invention, what I 90 consider to be new and desire to have protected by Letters Patent will be pointed out in the appended claims.

What is claimed is:

1. In a telephone system, an automatic switch for extending a connection to a line, after being first operated and released, said switch including a pair of line wipers, a source of signaling current, said source being normally associated with one of said 95 wipers, and means responsive to a preliminary operation of said wipers corresponding to a particular digit for transferring said source into association with the other wiper.

2. In a telephone system, a two-party line 105 having substation ringers connected from opposite sides of said line to ground, an automatic switch for extending a connection to said line, means for preliminarily operating and releasing said switch, a source of signaling current, and means in said switch for applying said source to one side or the other of said line depending upon the extent of 110 said preliminary operation.

3. In a telephone system, a party line connector switch responsive to a plurality of digits in a called number, two-party lines and levels of selectable terminals therefor in said switch, a source of signaling current, and electro-magnetic means for operating 115 said switch, said means responsive to the first one of said digits for raising said switch to a desired level and releasing same and responsive thereafter to one or more digits for selecting the terminals of one of said 120 party lines and for applying said source to one or the other side of the line depending upon whether said switch was raised to a predetermined level or not responsive to the first digit.

4. In a telephone system, a connector switch including a pair of line wipers and responsive to a plurality of digits in a called number, electro-magnetic means responsive to the first digit for stepping said switch to any desired level and releasing same, a source of signalling current normally associated with one wiper, and a wiper reversing relay responsive when said switch is raised 10 to or beyond a predetermined level on said first digit for associating said source with the other wiper.
5. In a selective ringing party line connector switch provided with a pair of wipers having primary and secondary movements, a wiper reversing relay, and means for energizing said relay responsive to a predetermined primary movement.
6. In a telephone system, a plurality of 20 two-party and direct lines, a connector switch responsive to three digits in a called number, and electro-magnetic means responsive to the first digit for stepping said switch to any desired level and releasing same, said first digit thereby controlling means for ringing over one side or the other of said lines as well as serving as a location identification.
7. In a telephone system, an automatic 25 switch for extending a connection to a line, said switch including a pair of line wipers, a source of signalling current, said source being normally associated with one of said wipers, means for repeatedly operating the switch to determine which party on the desired line is to be signalled and to select the line, means for releasing the switch responsive to its first operation, and means dependent upon the extent of said first operation for transferring said source into association with the other wiper.
8. In a selective ringing party line connector switch having primary and secondary movements, a wiper reversing relay, means for energizing said relay responsive to a predetermined primary movement, and means for restoring the switch upon completion of said primary movement.
9. In a telephone system, a connector switch having line wipers, means for moving said wipers in three successive movements to establish a connection, means effective upon the completion of the first movement for causing the restoration of the wipers, signalling means, and means depended upon the extent of the first movement for connecting said signalling means to one or the other of said wipers.
10. In a telephone system, a connector having line wipers and talking conductors, a reversing switch for connecting said conductors to said wipers, means for operating said wipers in accordance with certain successive digits in a desired number, means for releasing said connector after it has been operated in accordance with the first of said digits and before it has been operated in accordance with the remaining digits, and means effective if the first of said digits is greater than a certain amount to cause the operation of the reversing switch.
11. In an automatic telephone system, the method of establishing connections to a desired party on a party line which consists in operating a connector in accordance with one digit in the desired number, in conditioning the connector to signal the line over one or the other of the talking conductors depending upon the extent to which the connector is operated, and in then first releasing the connector and then reoperating it to select the desired line.

In witness whereof, I hereunto subscribe my name this 25th day of August, A. D. 1925.

ROY F. GOULD.
